CLAIM

The ornamental design for a prosthetic device insert as shown and described.

DESCRIPTION

FIG. 1 is a top view of a first embodiment of a prosthetic device insert design showing my new design; FIG. 2 is a bottom view of a first embodiment of a prosthetic device insert design showing my new design; FIG. 3 is a side view of a first embodiment of a prosthetic device insert design showing my new design; FIG. 4 is an opposite side view of a first embodiment of a prosthetic device insert design showing my new design; FIG. 5 is a front view of a first embodiment of a prosthetic device insert design showing my new design; FIG. 6 is a back view of a first embodiment of a prosthetic device insert design showing my new design; FIG. 7 is a top view of a second embodiment of a prosthetic device insert design showing my new design; FIG. 8 is a bottom view of a second embodiment of a prosthetic device insert design showing my new design; FIG. 9 is a side view of a second embodiment of a prosthetic device insert design showing my new design; FIG. 10 is an opposite side view of a second embodiment of a prosthetic device insert design showing my new design; FIG. 11 is a front view of a second embodiment of a prosthetic device insert design showing my new design; and, FIG. 12 is a back view of a second embodiment of a prosthetic device insert design showing my new design.
